UNITED STATES PATENT OFFICE.

WILHELM SCHNIPPA, OF SCHWEPNITZ, SAXONY, GERMANY.

DESIGN FOR A NURSING-BOTTLE.

45,128.

Specification for Design.

Patented Jan. 6, 1914.

Application filed August 9, 1913. Serial No. 783,942. Term of patent 7 years.

To all whom it may concern:

Be it known that I, WILHELM SCHNIPPA, a subject of the King of Saxony, residing at Schwepnitz, Saxony, Germany, have invented a new, original, and ornamental Design for Nursing-Bottles, of which the following is a specification, reference being had to the accompanying drawing, forming part thereof.

Figure 1 is a front view of a nursing bot-

tle, showing my design, Fig. 2 a side view, and Fig. 3 a plan thereof.

I claim:

The ornamental design for a nursing bottle, as shown.

WILHELM SCHNIPPA.
